UNITED STATES PATENT OFFICE.

PETER MAST, OF WATERVILLE, OHIO.

WIRE FENCE.

SPECIFICATION forming part of Letters Patent No. 449,373, dated March 31, 1891.

Application filed June 14, 1890. Serial No. 355,498. (No model.)

To all whom it may concern:

Be it known that I, PETER MAST, of Water-
ville, in the county of Lucas and State of
Ohio, have invented certain new and useful
5 Improvements in Wire Fences; and I do
hereby declare that the following is a full,
clear, and exact description of the invention,
which will enable others skilled in the art to
which it appertains to make and use the same,
10 reference being had to the accompanying
drawings, and to the figures of reference
marked thereon, which form part of this
specification.

My invention relates to an improvement in
15 wire fences of that character in which a se-
ries of wires are put in tension longitudi-
nally and properly supported the desired dis-
tance apart, and to which are woven a series
20 of transverse wires, which not only support
the longitudinal wires between the posts and
prevent the same from sagging, but add to
the appearance of the fence and render the
same the better adapted to turn the stock.

One object of the invention is to provide an
25 inexpensive and effective brace for the end
portion of the fence by which to compensate
for the strain exerted by the tightening de-
vices, as well as the expansion and contrac-
tion of the wires due to climatic changes.

30 A further object is to provide a tension de-
vice that shall be convenient of operation,
positive in action, and durable.

A further object is to provide an improved
35 clamp for securing the wires to the post, where-
by I am enabled to employ a single rectangu-
lar bar of iron for each post.

The invention consists in the parts and
combination of parts hereinafter described,
and pointed out in the claims.

40 In the drawings forming part of this spec-
ification, and in which like numerals of refer-
ence indicate like parts, Figure 1 is a side elev-
ation of a portion of fence constructed in ac-
cordance with my invention. Fig. 2 is a side
45 elevation of my improved turn-buckle and
connecting-plates. Fig. 3 is a transverse sec-
tion of a post, showing the clamp secured
thereon and embracing one of the longitudi-
nal wires, this view being taken on line $\alpha\alpha$
50 of Fig. 1. Fig. 4 is a like view showing a
clamp for holding the wire to the posts inter-

mediate the end posts, this view being taken
on line $\gamma\gamma$ of Fig. 1. Fig. 5 is a detail view
of a portion of the turn-buckle, showing the
winged nut for embracing the tension-plate. 55
Fig. 6 is a rear elevation of the end post, show-
ing the means employed for bracing the same
from inclining sidewise.

1 designates the post, preferably formed of
a rectangular bar of metal, which, after be- 60
ing driven into the ground a proper distance,
is stayed or anchored by means of anchor-
plates 2, secured thereto by means of clamps
3, (see Fig. 4,) wherein the same form of clamp
is shown as applied to the posts for holding 65
the wire in place.

4 designates the end post, to which the ends
of the wires comprising a section of fence are
secured, usually by wrapping the same around
the post and twisting the wire upon itself, as 70
shown. In order to brace the end post and
thereby secure a proper tension to the wires,
a post 5 is secured in the ground a short dis-
tance forward of the end post with the flat side
of the post against the wires, which are each 75
secured to the post by means of a clamp 6, (see
Fig. 3,) consisting of two plates 7, perforated to
allow bolts 8 to be passed through the same,
which, when put in tension by nuts 9 run there-
on, clamp the wires firmly to the post. This, 80
together with the end post, is braced by means
of a bar 10, secured to the upper portion of post
4 and inclining toward post 5, and preferably
extending a short distance into the ground
about midway between the posts, the lower 85
end being secured from forward movement by
means of a wire 11, secured thereto and to post
4, there being a wire 12 secured to the lower
end of bar 10 and to the upper end of post 5,
whereby when tension is put upon the longi- 90
tudinal wires any tendency to inclination of
the post 5 in the direction of tension is com-
municated to the wire 12 and to bar 10, caus-
ing the latter to bear with like force in an op-
posite direction upon post 4.

95 My improved tension device comprises
plates 13 of curved form and perforated cen-
trally to receive the end of a right-and-left-
hand-threaded bolt 14, formed with an en-
largement 15 to receive a wrench by which to 100
turn the bolt when screwing the same into
nuts 16, bearing upon the inside of plate 13,

and formed with projections 17 bent at right angles to the body of the nut to embrace the plate 13 to prevent revolution of the nut.

It will be understood that by reason of the 5 curved formation of the plates 13 the draft of the wires (which are secured to each end thereof by being passed through perforations formed therein) upon the plate is longitudinally with the end portion, thereby giving 10 greater resiliency to the plate to allow of expansion and contraction of the wires when affected by climatic changes, and the use of the winged nuts not only obviates the necessity of threading the plates for the reception 15 of the bolt 14 and the liability of stripping the thread in the plate by reason of the lightness of the metal, but by the use of the winged nuts an independency of action of the plates is provided for, whereby the same may rock 20 upon the nut to allow of securing wires of irregular lengths thereto, as the plate by this arrangement may rock upon the nut to incline in either direction should one wire be of less length than the other.

25 The clamp shown in detail in Fig. 4 is designed for use upon the posts intermediate the end posts and formed in U shape, each end thereof being threaded to receive nuts which bear upon a plate 3', perforated to receive 30 the ends of the clamp which embraces the post with one portion above the wire and one below the same, the plate bearing directly upon the wire and holding the same firmly when the nuts are screwed firmly against the 35 plate.

In order to properly brace the end post, I employ a wire 18, which may be passed through perforations in the post or wrapped around the same, as shown, with the ends of the wire 40 inclined in opposite directions therefrom and passed through perforations in stakes 19, which are driven into the earth, by which means all possibility of lateral inclination of the post is avoided.

45 20 designates a bar, which, when the wires are put in proper tension, is passed between alternate bolts 14, thereby closing the openings caused by the discontinuance of the wire sections, this bar being perforated to receive 50 a wire hook 21, which, when engaged with the upper bolt 14, sustains the sections at this point and prevents sagging.

By the construction described the end post is firmly braced at a minimum expense, and 55 tension is secured upon the wires by a ten-

sion device, which allows of ready access to the bolts and an independent action of the plates, which, by reason of their curved formation, may be of lighter material than if formed of straight plates.

Having thus fully described my invention, what I claim as new, and desire to secure by Letters Patent, is—

1. In a wire fence constructed in sections, a series of curved resilient tension-plates, 60 each perforated centrally and at its ends, the latter perforations to receive two of the longitudinal wires in the same section, in combination with a right-and-left-hand-threaded bolt passing loosely through the said central perforations, and threaded winged nuts embracing the plates and engaging the said bolt.

2. In a wire fence constructed in sections, a series of tension devices to which the wires forming the fence are secured, in combination with a bar arranged alternately in front of and in rear of the respective bolts of the tension devices and having means for engaging the bolt of the upper tension device, for the purposes set forth.

3. As a new article of manufacture, a tension device for wire fences, comprising two curved resilient plates, each perforated centrally and at its ends, a right-and-left-hand-threaded bolt engaging the central perforation, and winged nuts on said bolt adapted to embrace the said plates.

4. In a wire fence, the combination of two vertical posts, a rigid bar connected with the top portion of the first post and inclined 90 therefrom, a flexible connection attached horizontally to the said post and to the brace-bar near their lower ends, and an upwardly-inclined flexible support connecting with the lower end of the said bar and with the upper 95 portion of the second post.

5. In a wire fence, the combination of two posts, a rigid brace-bar connected with one of the posts and inclined therefrom, and a flexible connection uniting the lower end of 100 the brace-bar with the lower portion of one post and the upper portion of the other post.

In testimony that I claim the foregoing as my own I hereby affix my signature in presence of two witnesses.

PETER MAST.
